STAMPING DEVICE

Carl Ludewigs, Hamburg, Germany, assignor to "Luka" Handelsgesellschaft Ludewigs & Kahlcke, Hamburg, Germany, an association of Germany

Application June 26, 1933, Serial No. 677,726
In Germany March 22, 1933

5 Claims. (Cl. 101—327)

This invention relates to a stamping device.

Stamping devices, particularly for marking and cancelling tickets, are known which have a stamp carrier provided at its lower end with a printing stamp and held in a guide by spring action. Moreover such stamping devices have already been arranged in such manner that the shaft of the stamp serves for receiving the supply of ink. During the depression of the shaft of the stamp an inking roller mounted on a pivoted carrier bears against the surface of the ink reservoir and said roller is urged against the surface of the ink reservoir which is arranged in the shaft of the stamp and said roller is impregnated with ink; on the return motion of the shaft of the stamp and of the inking roller the latter inks the stamp.

Such stamping devices are suitable not only for marking and cancelling tickets but could also be used as other stamps of any desired size.

However it has been found that the ink if supplied through the shaft of larger stamps will not be evenly distributed over the latter, so that perfectly uniform impressions cannot be obtained.

According to the invention, this drawback can be overcome by mounting the stamp on an ink reservoir consisting of a box which is open on one side and filled with absorbent material, such as cotton. The open side of the box is closed by a perforated plate over which a tubular wick is drawn. Being filled into the reservoir by a pipe, the ink is taken up by the absorbent material which transmits it to a wick whence it is supplied by a roller to the stamp which is thus inked.

It has further been found advisable to attach the inking roller tensioned by spiral springs and secured to two arms by means of the latter to two pivotal levers also subjected to spring tension. When the outer sheath is moved into the inner sheath, these levers are carried along and the inking roller is passed over the wick preparatory to re-inking the stamp during the return movement. Owing to this arrangement, the path to be travelled by the inking roller is much shorter than it would be if the roller were secured to the inner wall of the casing by its arms, and the casing can thus be made correspondingly shorter and handier.

A particular advantage of the arrangement resides, moreover, in that it could be adapted in a simple way for a number of interchangeable stamps, so that a single device could be employed

with a number of stamps without having to screw the stamps in and out for securing the same.

This simple interchangeability of the stamps could be obtained in various ways.

For example, each stamp is secured on a block 5 of rectangular cross section. This block fits in a resilient sleeve open below and on the side and carried on the ink reservoir. In addition, a pin is provided at the closed end of the sleeve and a corresponding hole is provided in the block. 10 By using such stamp carrying blocks the stamps could be rapidly and simply interchanged.

Further, the various stamps could be secured one on each surface of a multi-faced block of triangular, rectangular or like cross section 15 which is rotatably mounted in bearings carried on the ink reservoir and can be rotated about its axis by means of a knob or the like, the block being retained in the correct position at any time by means of a leaf spring, for example. 20

According to a further embodiment, the various stamps are secured in known manner on endless rubber bands which run on a rotatable roller and over a fixed roller and can be moved by means of discs provided on the rotatable roller. This arrangement could be carried out in known manner in subdivision as a date stamp, for example. 25

By way of example, three embodiments of the invention are illustrated in the accompanying 30 drawings, in which Figure 1 is a front view, partly in section; Figs. 2 and 3 are sectional side views of the device provided with an interchangeable block carrying the stamp; Fig. 4 is a side view, partly in section, of a device in which the stamps 35 are disposed on the faces of a triangular rotatable block; Fig. 5 is a side view, partly in section, of a device provided with stamps secured on endless rubber bands; Fig. 6 is a top view of the ink reservoir; and Fig. 7 shows, partly in section, 40 how the inking roller is secured.

Referring to the drawings, the ink reservoir 2 is secured by screws to a side wall of the outer sheath 1 and provided with the filling tube 3 which is closed by a screw. The ink reservoir 2 45 filled with cotton or the like and carries on one side the perforated plate 4 over which the inking wick 5 is drawn which inks the inking roller 6 subjected to the action of helical springs when the inner sheath 8 is forced inside the outer 50 sheath 1 against the action of the helical spring 9 whereby the free end of the ink reservoir 2 approaches the opening 10 in the inner sheath 8. The inking roller 6 is held in position by the arms 14 which are articulated to the levers 18 ten- 55

sioned by the springs 23, and the levers 18 are driven by the shoulders 25 of the inner sheath 8 when the latter is forced into the outer sheath 1. The interchangeable stamps are arranged on, 5 over or adjacent the free end of the ink reservoir

2. When the sheath 8 is pushed into the sheath 1, the knob 26 secured to a flat spring will engage the hole 27 and thus hold the sheaths in position.

In the embodiment according to Figs. 1 and 2 10 the spring sheath 11 which is open at the bottom and on the side and provided at its closed end with the pin 12 is secured to the ink reservoir 2. The block 13 carrying the stamp and provided at its underside with a recess corresponding to the 15 pin 12 is inserted in this sheath 11.

In the embodiment shown in Fig. 4 the bearings 15 are provided on the ink reservoir 2 and serve as support for the rotatably mounted block 16 which is triangular, for example, and on the surfaces of which three different stamps can be 20 fixed. The block 16 is held in a predetermined position by means of the leaf spring 17.

In Fig. 5, the stamps secured on endless rubber bands 18 are disposed adjacent the ink reservoir 25 2. The rubber bands 19 run over the upper shaft 23 which can be rotated by means of the rollers 21 and over the lower fixed shaft 22. Since there is little space available, the ink reservoir 2 has preferably a slot 24 through which the ink may 30 pass to the wick 5 and saturate the latter. For the same reason, the arms 14 which hold the inking roller 6 are resiliently secured directly to the inner wall of the sheath 8.

On displacing the inner sheath 8 into the outer 35 sheath 1 the stamp pushes to one side the inking roller 6 which is subjected to the action of the spring 1. During further displacement of the sheath 8 the inking roller 6 engages the wick 5, is supplied with ink and thus can re-ink the 40 stamp on the return motion to the original position.

I claim:—

1. In a stamping device an ink reservoir consisting of a box filled with absorbent material, 45 said box being open on one side; a perforated

plate for closing the open side of said box, an inking wick covering the said plate, an inking roller, two resiliently held arms for carrying said inking roller, and two spring-actuated levers articulated to said arms. 5

2. In a stamping device an ink reservoir consisting of a box filled with absorbent material, said box being open on one side, a perforated plate for closing the open side of said box, an inking wick covering the said plate, a replaceable 10 block carrying the stamp and being recessed, a suitably supported inking roller, a resilient sleeve secured to the ink reservoir for receiving said block, and a pin in said sleeve for engaging the recess in said block. 15

3. In a stamping device an ink reservoir consisting of a box filled with absorbent material, said box being open on one side, a perforated plate for closing the open side of the said box, an inking wick covering the said plate, a suit- 20 25 ably supported inking roller, a plurality of bearings carried on the inking reservoir, a polygonal block rotatably mounted in said bearings, and a plurality of stamps carried by said block.

4. In a stamping device, a plurality of endless rubber bands, shafts from which the endless rubber bands are movable, stamps secured to said bands, an apertured ink reservoir adjacent to the stamps, a wick supplied with ink through the aperture of the reservoir, and a suitably mounted 30 ink roller supplied with ink from said wick and operative to ink the stamps.

5. A stamping device comprising an ink reservoir consisting of a box filled with absorbent material, said box being open on one side, an apertured plate for closing the open side of said box, an inking wick covering the said plate, stamping means in operative relation to the reservoir, an inking roller, means for mounting the inking roller for movement with relation to the stamping means and the reservoir whereby the inking roller is supplied with ink by said roller for inking the stamping means. 35 40
